UNITED STATES PATENT OFFICE.

PAUL F. DUSHA, OF NEW YORK, AND ANTON FEYK, OF BOHEMIA, NEW YORK,
ASSIGNORS TO HOLUB-DUSHA COMPANY, OF NEW YORK, N. Y., A CORPORA-
TION.

PEARL-BUTTON MACHINE.

1,343,042.

Specification of Letters Patent.

Patented June 8, 1920.

Application filed October 17, 1919. Serial No. 331,339.

To all whom it may concern:

Be it known that we, PAUL F. DUSHA and ANTON FEYK, citizens of the United States, and residents, respectively, of the city of 5 New York, borough of Manhattan, in the county and State of New York, and Bohemia, in the county of Suffolk and State of New York, have invented a new and Improved Pearl-Button Machine, of which the 10 following is a full, clear, and exact description.

This invention relates to pearl button machines and has particular reference to machines for making that type of buttons 15 known as shank buttons, and the present invention constitutes an improvement on the invention for which Letters Patent of the United States, No. 1,182,660 were issued on our application to Holub-Dusha Co., of New 20 York, on the 9th day of May, 1916.

Among the objects of the present invention are first to provide a means for steady- 25 ing or holding the drill near its point and irrespective of its length from the drill spindle so as to prevent the bending, breaking or buckling of the drill; secondly to reduce to a minimum the likelihood of breaking or splitting of the buttons while being drilled; thirdly to provide improved facil- 30 ities for easily and quickly adjusting the button holding chuck with respect to the path of movement of the series of drills around the general axis of the machine, and fourthly the provision of ejecting means for 35 positively and mechanically starting the button after being drilled from the holding chuck so that the pneumatic appliances, or their equivalent, relied upon for receiving and delivering the button from the drill 40 press will be sure to operate satisfactorily.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a vertical central sectional view of one of our improved button holding chucks and parts immediately associ-

ated therewith, the section being on a plane 55 substantially radial with respect to the axis of the machine.

Fig. 2 is a front elevation of the same, but with parts in vertical section substantially in a plane tangent to the path of movement of the drills around the axis of the entire machine.

Fig. 3 is a view somewhat similar to Fig. 1 but indicating the action of the button ejector after the button has been drilled. 65

Fig. 4 is an enlarged detail view of the drill guide and button holder.

Fig. 5 is a front elevation of the same, parts being in section on the line 5—5 of Fig. 4. 70

Fig. 6 is an enlarged vertical sectional view of the drill guide and button holder.

Fig. 7 is an outside elevation of the same as it would appear looking toward the right in Fig. 6; and 75

Fig. 8 is a lower end or plan view of the same.

Referring now more specifically to the drawings we show at 10 a drill spindle having a chuck 11 for holding a drill 12 of any 80 suitable caliber or length, the same usually and preferably being relatively small in diameter and of any convenient length whereby a single drill may be used for a long time before requiring to be renewed. 85

A button B having a shank b is shown held in a chuck 13 having a spindle 14 of tubular form. In the drilling of a hole in the shank of a button of this type it is desirable that the hole be drilled as nearly as 90 possible to the under or back face of the button, and it is to be noted also that the axis of the drill and hole formed thereby should coincide with the axis of the chuck spindle. Consequently the said back face of 95 the button lies in a plane substantially tangent to the geometric cylinder described by the drill in its revolution around the axis of the machine, it being understood that the structure of Fig. 1, for example, is but one 100 unit of a machine involving a large number of such units arranged so that the drills all revolve in the same path around said machine axis, as shown for instance in Letters Patent of the United States No. 1,206,518, 105 issued at our request to Holub-Dusha Co. on the 28th day of November 1916.

In view of the length and flexibility of

the drill 12 below the chuck 11 that may obtain in some instances and for the purpose of holding the drill steady and preventing the bending or buckling thereof we provide 5 a drill guide as shown in detail in Figs. 6, 7 and 8 and comprising a body 15 substantially cylindrical in form and having a bore 16 of a size corresponding to the diameter of the drill to operate therethrough while 10 the upper end of the bore 16 is counterbored at 16^a and provided with a taper 16^b where the two bores merge into each other. This taper insures the direction of the drill point down through the hole 16 when being 15 brought into operating position. The lower end of the guide is notched away at 17 to a plane tangent to the side of the bore 16 for the accommodation of the rim of the button and thus providing for the action of the 20 drill close to the back face of the button. Opposite the notch 17 the lower end of the guide is beveled off at 18 forming a sort of chisel point 19 at the lower end in the plane of the drill bore 16 and this chisel edge is 25 undercut in arc shape at 20 for direct contact with the upper side of the shank being drilled. The upper or crest portion of the undercut 20 is notched out at 21 to provide proper clearance for the chips. 30 It will be understood from the foregoing description that the chisel end 19, or its undercut 20 will bear directly upon the button shank and hold the button steady while the guide body as a whole constitutes 35 a steadyng device for the end of the drill. Hence it will be appreciated that the drill may be of any considerable length between the guide 15 and the chuck 11. The guide, serving to hold the drill from bending or buckling, prevents the button shank from 40 breaking or splitting.

As above premised the plane of the button B in the operation of our machines should be substantially tangent to the geometric 45 cylinder described by the drill in its revolution around the axis of the machine, and therefore it is important that the adjustability of the chuck 13 around the axis of its spindle be made as easy and convenient as possible, and when once properly adjusted with respect to the tangent aforesaid that it be held firmly from rotation around the axis of the spindle. To accomplish these results we provide a thimble 22 through which the 50 lower end portion of the spindle 14 projects and against which a nut 23 bears, the nut being threaded upon said spindle extension. A lug 24 is fitted in the thimble and projects into a slot 25 formed in the lower end 55 of the chuck holder 26 and so the thimble is held from rotation in the frame of the machine but is left free for vertical movement with the chuck for inserting or removing a button as in the usual practice of the 60 machine. As indicated in Figs. 2 and 3 the 65

chuck holder is adapted to be lowered for loosening the chuck, by means of a cam 26^a beneath which a projection 26^b from the holder rides during the revolution of the chucks, as aforesaid. Upon the loosening of 70 the nut 23 the chuck 13 may be adjusted freely around its axis and upon the tightening of the nut again such adjustment is made positive and secure.

In the usual practice of button making 75 or drilling machines the buttons after being drilled are removed or delivered from the chucks by pneumatic means and it sometimes occurs that the buttons stick in the chucks or for some reason the pneumatic 80 force fails to unseat them. In order to obviate this difficulty we provide automatic mechanical means for starting the buttons from the chucks so as to bring them into 85 position to be caught by the pneumatic delivery means. To this end we provide an ejector 27 comprising a straight bar or a round rod located within the spindle 14 and movable longitudinally thereof toward and from the button. As in the previous patent above specified there is provided a V-shaped button seat 28 upon or within which the shank b of the button is directly supported and which serves to center the button in one direction. The face or body portion 90 of the button projects alongside of the button seat 28. The active end of the ejector 27 is notched out at 29 so as to bring the extended finger portion 30 thereof in normal position at one side of the button seat 100 28 and just below the periphery of the face of the button as shown in Figs. 1 and 2. At the lower end of the notch 29 is provided a shoulder 31 which in abutting against the bottom of the button seat will limit 105 the upward throw of the ejector. Any suitable means may be provided to actuate the ejector 27 when the button is to be delivered as in Fig. 3. To this end we provide a plunger 32 housed in cam operated mechanism 110 beneath the spindle holding devices and at the proper time the spindle chuck is loosened to release the button and several parts of the mechanism are so operated relatively to one another as to cause the 115 plunger 32 to enter the lower extension portion of the spindle and force the ejector 27 upward so that the removal of the buttons by pneumatic or other means will be positively assured.

120 We claim:

1. In a machine for drilling shank buttons, the combination with a drill, means to rotate the drill around its axis, and means to support a button with the shank in said 125 axis and with the spot to be drilled close to the plane of the back face of the button, of a device constituting a combined button shank holder and drill guide, said device being located between the button and the drill 130

holder and having an undercut chisel edge to engage the button shank on opposite sides of said spot.

2. In a pearl button machine, the combination of a button holding chuck having a button seat for supporting and centering the button shank, means providing for the adjustment of the chuck around its axis to properly position the button with respect to the path of movement of the chuck around the axis of the machine, means to permit the necessary vertical movements of the chuck for grasping or releasing a button without interfering with the adjustment thereof aforesaid, and means to drill a hole through the button shank.

3. In a pearl button machine, the combination of a chuck having a button shank holding seat, means to control the vertical movements of the chuck for gripping and releasing the button held upon the seat, and means providing for the adjustment of the chuck around its axis and to maintain such adjustment irrespective of the vertical movement aforesaid.

4. In a pearl button machine, the combination of a button holding chuck including a shank support for holding a button in a certain position with respect to the path of movement of the button in its orbit around the axis of the machine, means providing for the adjustment of the chuck around its axis and to lock the same in such adjustment to prevent rotation of the chuck around its axis, means providing for the reciprocations of the chuck for gripping and releasing the button independently of

the aforesaid adjustment means, and means acting upward through the chuck to eject the button from its seat after being drilled. 40

5. In a pearl button machine, the combination of a button holding chuck having a tubular spindle, means to reciprocate the chuck for causing the same to grip or release the button, means to prevent rotation 45 of the chuck and spindle irrespective of the reciprocation thereof, and a button ejecting member located in the spindle and movable longitudinally thereof, substantially as set forth. 50

6. In a button machine, the combination of a chuck having a tubular spindle, means to reciprocate the chuck and spindle to cause the same to grip or release a button, means to prevent rotation of the chuck 55 around the axis of the spindle, and plunger means acting longitudinally through the spindle to positively eject the button from the chuck after being drilled.

7. In a machine for drilling the holes in shank buttons, the combination of a chuck to receive and hold a button edgewise, said chuck having a seat for supporting and centering the button shank, an ejector movable upward along the axis of the chuck to 65 positively eject the button after being drilled, said ejector being notched out at one side of its active end to accommodate the button seat and provide a finger at one side of the seat for action against the periphery 70 of the button, and means to operate the ejector.

PAUL F. DUSHA.
ANTON FEYK.
